UNITED STATES PATENT OFFICE.

FLORENCE L. GRANT AND CARL A. BROWN, OF FOSTORIA, OHIO, ASSIGNEES TO
GENERAL ELECTRIC COMPANY, A CORPORATION OF NEW YORK.

DESIGN FOR A LAMP SHADE OR REFLECTOR.

45,629.

Specification for Design.

Patented Apr. 21, 1914.

Application filed August 7, 1913. Serial No. 783,622. Term of patent 7 years.

To all whom it may concern:

Be it known that we, FLORENCE L. GRANT and CARL A. BROWN, citizens of the United States, residing at Fostoria, in the county of Seneca and State of Ohio, have invented a new, original, and ornamental Design for Lamp Shades or Reflectors, of which the following is a specification, reference being had to the accompanying drawing, forming part thereof.

The figure is an elevation of a reflector

substantially circular in plan showing our new design.

We claim—

The ornamental design for a lamp shade or reflector as shown.

FLORENCE L. GRANT.
CARL A. BROWN.
